NAIL PULLING DEVICE

Walter N. Henry, Dayton, Ohio

Application February 16, 1951, Serial No. 211,220

11 Claims. (Cl. 254—19)

1

This invention relates to a power-operated tool for pulling nails.

The invention has particular application to apparatus for use in opening nailed containers such as boxes and crates in factories, stores and other establishments in which such operation is conducted substantially on a quantity basis as a regular activity, but may be used in all cases in which it is desired to withdraw nails, staples or the like from a surface in which they are embedded, particularly where it is desired to leave the surface material sufficiently undamaged for reuse.

Such work is ordinarily done by means of hand tools, the use of which has a tendency to mar and break the wood so that it cannot be used again. Because of the physical strength necessary to use the tools, it is ordinarily required to be done by men. The amount of work that can be done by each workman each day by the ordinary method is, moreover, relatively limited.

It is accordingly one of the principal objects of the invention to provide a power-operated tool for quickly and easily pulling nails and the like from a surface in which they are embedded and with minimum damage to the surface.

Another object is to provide power-operated apparatus for opening boxes, crates and the like on a quantity basis in a substantially shorter unit time than heretofore accomplished in order to increase the volume of work which may be done in a given time by each operator.

It is a further object of the invention to furnish a device for opening boxes, crates and the like operated by power rather than by muscular strength, so that it may be used in industry by women and boys.

Additional objects of the invention are to provide a power-operated nail pulling device which is relatively light in weight, which is relatively simple yet strong and certain in operation, and which may be produced at reasonable cost.

Other objects and advantages of the invention will be apparent from the following description, the accompanying drawings and the appended claims.

In the drawings—

Fig. 1 is a side elevation, partly broken away and in section, showing a power-operated nail pulling device in accordance with the invention;

Fig. 2 is a longitudinal sectional view on the line 2—2 of Fig. 1;

Fig. 3 is an end view showing the bottom or jaw end of the device;

Fig. 4 is a section on the line 4—4 of Fig. 2;

2

Fig. 5 is a detail perspective view on an enlarged scale of one of the jaw members of the device;

Fig. 6 is a detail perspective view of a part of one of the jaw-operating members of the device;

Fig. 7 is a section on the line 7—7 of Fig. 1;

Fig. 8 is a fragmentary section showing the jaws embedded in a surface surrounding a nail to be pulled at the beginning of the jaw-closing movement;

Fig. 9 is a fragmentary section similar to Fig. 8 showing the jaws closed on the nail, which is partially withdrawn;

Fig. 10 is a side elevation with the casing in section showing the relative positions of the parts at the conclusion of a nail pulling operation; and

Fig. 11 is an elevational view of another form of construction of the device, having a self-contained power source.

Referring to the drawings, which illustrate preferred embodiments of the invention, the device as shown includes an outer casing 20, shown as in two parts, and an inner casing 21, to which are affixed respectively handles 22 and 23, handle 23 projecting through a suitable slot 24 in the outer casing and being affixed at its upper end only in order to extend over the outer casing. A rotatable shaft 25 having threaded portion 26 is mounted within inner casing 21 and is adapted to be attached to a power source, not shown, by a flexible driving connection 27 or other suitable means. The drive shaft 25 is supported at its upper end by a ball-bearing 28, and at its lower end by an enlarged portion 30 in a bushing 31 press-fitted into a web 32 in the interior of inner casing 21 and retained in position by a further enlarged portion 33 of the shaft. Bearing 28 may be press-fitted into a suitable aperture in the top 34 of inner casing 21 and held in place by cap 35 retained by screws 36 or other suitable means, and as shown, bearing 28 is preferably constructed to serve as both a radial and thrust bearing for shaft 25.

A hammer member 40 is mounted within inner casing 21 for rotational and reciprocating movement in cooperation with an anvil member 41 and is operatively connected with shaft 25 by means of a slot 42 which receives a corresponding flattened end portion 43 of the shaft. The hammer member may thus slide axially on the shaft but will be rotated by it, and it is normally biased downward by spring 44 surrounding a reduced portion of the hammer member and compressed between the enlarged portion 33 on shaft 25 and an enlarged head portion 45 of the hammer mem-

ber. The upper end portion of anvil member 41 is also enlarged so that both members fit in guided relation within inner casing 21, and both the hammer member and anvil member are provided on their adjacent faces with helically curved cam surfaces 50 and 51, respectively, adapted to cooperate with each other alternately as the hammer member 40 is rotated to force the latter axially of casing 21 and against spring 44 away from anvil member 41 and then to release the hammer and permit it to strike the anvil under the urging of spring 44.

The anvil member 41 includes a lower portion splined for sliding movement in the reduced lower end portion 52 of inner casing 21. A carrier member 53 for the nail pulling jaws 55 is secured to the lower end of the anvil, as by the threaded connection at 56, for movement therewith as a unit, and these parts are normally biased downwardly by the spring 57 seating against shoulder portions on the member 53 and inner casing 21 as clearly shown in Fig. 2. The lower end of carrier member 53 is slotted to form a fork for receiving jaws 55, which are pivoted therein by means of pins 58 in bores 59 and are normally biased to open position by a spring 60 as shown in Fig. 2, and the jaws may be provided with serrated nail gripping edges 61 (Fig. 5).

The jaws 55 are adapted to be closed into nail gripping position by an inwardly tapered collet portion 65 at the lower end of outer casing 20 which operates the jaws through a pair of fingers 66 pivoted at their upper ends by pins 67 in slots at either side of casing 21. At its lower end, each finger 66 (Fig. 6) carries a roller 70 for reducing friction with the collet 65, and the inner side of the lower end of each finger 66 is channeled at 71 for guided engagement with lugs or pads 72 on the backs of the jaws 55 which fit slidably within the channels 71. Thus if outer casing 20 is moved downwardly with respect to the inner casing, the collet 65 will press fingers 66 inwardly against jaws 55 and thereby force the nail gripping lower portions of the jaws towards each other and into gripping position.

A selectively operable driving connection is provided for causing relative axial movement of the inner and outer casings to effect closing of jaws 55 as described, and thereafter to cause the nail gripped in the closed jaws to be withdrawn. This connection includes a partly hollow block 75 straddling shaft 25 and having a threaded half-circular portion 77 adapted to engage the threaded portion 26 of shaft 25. At one end block 75 includes upwardly extending arms 78 in which a lever 79 is pivotally mounted at 80, and at its opposite end block 75 includes a pin portion 81. Block 75 extends through projections 82 and 83 on the wall of casing 20, projection 83 being provided with a cap 84. A spring 85 is mounted on pin 81 between the end of projection 83 and a washer 86 held on the end of pin 81 by means such as a cotter pin 87 to bias block 75 to the right as viewed in Fig. 1 and thus to disengage threads 77 from the threaded portion 26 of the shaft.

A block 90 is slidably received within block 75, and it includes a pin portion 91 which extends through a slot 92 in lever 79 and through a plate 93 held between the arms 78 outwardly of lever 79. At its inner end, block 90 includes a threaded half-circular portion 94 adapted to engage the threads 26 on shaft 25. A spring 95 is mounted on pin 91 between plate 93 and a washer 96 and cotter pin 97 on pin 91 to bias block 90 normally 75.

to the left as viewed in Fig. 1 and thus to hold threads 94 away from the shaft.

The lever 79 includes a boss 99 on either side of slot 92 which engage block 90, and thus if lever 79 is pushed towards casing 20, the blocks 75 and 90 will be forced towards each other to engage their respective threaded portions 77 and 94 with the threads 26 on shaft 25. Thus with shaft 25 revolving, the blocks will be caused to travel along the shaft and to carry outer casing 20 downwardly with respect to inner casing 21. Casing 21 has slots 100 on opposite sides to receive blocks 75 and 90 during this movement, as well as the slot 24 for similarly receiving handle 23, as described.

In operation, the operator holds the device in position substantially perpendicular to the surface in which the nail is embedded, with the open jaws on either side of the head of the nail.

20 Slight pressure forces the jaw assembly and anvil member 41 axially inward against the pressure of spring 51, bringing the cam surfaces 50 and 51 of hammer 40 and anvil 41 into contact. As hammer member 40 is rotated rapidly by shaft 25, the cam surfaces cooperate first to force it away from the anvil member, compressing spring 44, as shown in Fig. 2, and then to release it to be driven sharply against anvil member 41 by the release of this spring, producing a reciprocating hammering action to force jaws 55 into the surface against which the jaws rest as shown in Fig. 8 in position to grip the nail when the jaws are closed.

In order to close the jaws around the nail and to extract it, the operator then causes outer casing 28 to move axially of inner casing 21 by pressing the free end of lever 79 toward the casing, causing blocks 75 and 90 to move inwardly into cooperative engagement with the threaded portion 26 of shaft 25 and to travel downward along the rotating shaft as described, outer casing 20 serving during this movement both as a jaw-closing member and as a withdrawing member. As casing 20 moves downward, the jaws are caused to close into gripping relation with the nail by the collet 65 as shown in Figs. 8 and 9. As it continues its downward motion, its lower end comes into contact with the surface surrounding the nail and causes inner casing 21 and the closed jaws to move away from such surface until the nail is fully withdrawn (Fig. 10). The length of threaded portion 26 should be such that the closed blocks 75 and 90 will ride off the lower end thereof when withdrawal is completed. The operator then, by releasing lever 75, allows the blocks to be separated by the action of springs 85 and 95, and returns outer casing 20 manually by means of handles 22 and 23 to the position of Fig. 1. As jaws 55 are released from the pressure of collet 65 they are opened by spring 60, and the withdrawn nail drops out.

65 The area of the lower end of casing 20 pressing against the surface surrounding the nail while it is being withdrawn is sufficiently broad that there is little if any tendency for it to mark the surface. Additionally, all of the force used in extracting the nail is exerted outwardly, so that any tendency to push the nail sidewise and thus to increase friction during extraction, as is the case with the hand tools normally employed, is avoided. There is accordingly a minimum tendency to mar, break or otherwise to spoil the wood or other surface in which the nail

is imbedded, permitting such material to be reused. Thus use of the invention will greatly speed up the operation of withdrawing nails and permit substantial increase in the rate of work of an operator. Furthermore, since the physical strength necessary for operating the device is substantially only that necessary to hold it in position and it is relatively light in weight, only slight physical strength is required for its use, and it may easily be used by women and boys.

It is preferable that hammer member 40 and anvil member 41 should operate in a lubricating bath, and inner casing 21 is accordingly shown as being formed in two sections connected by a threaded connection at 101 to provide for adding lubricant when necessary, and also for simplicity in assembly. It may be advisable also for the lower portion of outer casing 20 to be made from steel or other material different from that of the upper portion, and as noted, outer casing 20 is similarly shown as being in two sections connected by a threaded connection at 102.

It is apparent that the force of the blows by hammer member 40 on anvil member 41 will depend on such factors as the weight of the hammer member, the strength of the spring 44, the length of the stroke, and the speed of rotation of shaft 25. It has been found in practice that a hammer member weighing slightly more than $\frac{1}{2}$ pound, rotated at a speed of approximately 1000 R. P. M. and with two cams 50 and 51 on each of the respective cam surfaces having a depth between their high and low points of approximately one-half inch, in cooperation with a spring exerting a pressure of approximately 60-80 lbs. when compressed, gives satisfactory results.

Fig. 11 shows a nail pulling device similar to that described in connection with Figs. 1 to 10 and including similar outer and inner casings 120 and 121 respectively. However, instead of a flexible connection to the drive shaft from an external drive source, Fig. 11 shows a motor 122 mounted directly on the upper end of the inner casing, either an electric or air motor being satisfactory. The construction and operation of this form of the invention is otherwise substantially the same as already described in connection with Figs. 1 to 10.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A power-operated nail pulling device comprising a casing, an anvil movable in said casing, nail-gripping jaws carried by said anvil and projecting from said casing, a drive shaft rotatable in said casing, means for connecting said drive shaft to a power source for rotation thereby, a driving member for said anvil mounted for reciprocation in said casing in response to rotation of said drive shaft for driving said anvil in a direction to force said jaws into the surface surrounding a nail to be pulled, a withdrawing member carried by said casing and extending adjacent said jaws in initially spaced relation with said surface, means for causing the closing of said jaws to grip said nail, and means for selectively connecting said drive shaft to said withdrawing member for causing relative movement thereof toward said surface and corresponding

movement of said jaws in gripping relation with said nail away from said surface.

2. A power-operated nail pulling device comprising a casing, an anvil movable in said casing, nail-gripping jaws carried by said anvil and projecting from said casing, a drive shaft rotatable in said casing, means for connecting said drive shaft to a power source for rotation thereby, a driving member for said anvil mounted for reciprocation in said casing on rotation of said drive shaft for driving said anvil in a direction to force said jaws into the surface surrounding a nail to be pulled, a withdrawing member carried by said casing and extending adjacent said

15 jaws in initially spaced relation with said surface, means operably connected with said drive shaft for causing the closing of said jaws to grip said nail, and means operably connected with said drive shaft for causing relative movement of said withdrawing member toward said surface and corresponding movement of said jaws in gripping relation with said nail away from said surface.

3. A nail pulling device comprising an anvil member, normally open nail-gripping jaws carried by said anvil member, a hammer member adjacent said anvil member and reciprocable with respect thereto, a drive shaft, means connected with said drive shaft for driving said hammer member against said anvil member in a direction to force said jaws into the surface surrounding a nail to be pulled, a withdrawing member adjacent said jaws and initially spaced from said surface, said withdrawing member having a portion adapted on movement thereof toward said surface to close said jaws to grip said nail, said withdrawing member having another portion adapted on movement thereof toward said surface to abut against said surface and to press said jaws in gripping relation with said nail away from said surface, and means for selectively connecting said withdrawing member with said drive shaft.

4. A nail-pulling device adapted for use with a power source, comprising a rotatable shaft adapted to be connected to said power source, a driving member operably connected with said shaft for rotation thereby, an anvil member adjacent said driving member, normally open nail-gripping jaws carried by said anvil member, means for biasing said driving member toward said anvil member, means on said driving member and said anvil member adapted to cooperate with said biasing means on rotation of said driving member for driving said anvil member in a direction to force said jaws into the surface surrounding a nail to be pulled, means for selectively closing said jaws in gripping relation with said nail, means movable relatively to said jaws for direct engagement with said surface to force said jaws and said nail away from said surface, and means for selectively connecting said movable means with said power source for causing said relative movement of said jaws and said movable means.

5. A power-operated device for pulling nails comprising a rotatable shaft adapted to be connected to a power source, a hammer member on said shaft adapted to rotate therewith and to move axially thereon, an anvil member adjacent said hammer member, a plurality of normally open nail-gripping jaws supported for movement with said anvil member, means biasing said hammer member toward said anvil member, complementary portions on said hammer member and

said anvil member adapted to cooperate with said biasing means to effect reciprocating movement of said hammer member with respect to said anvil member upon rotation of said shaft to drive said jaws into the surface adjacent a nail to be pulled, a withdrawing member adjacent said jaws in initially spaced relation with said surface, means for operation by said shaft to close said jaws in gripping relation with said nail, means for operation by said shaft for causing relative movement of said withdrawing member toward said surface and corresponding movement of said closed jaws and said nail away from said surface to extract said nail therefrom, and means for releasably connecting said shaft with said jaw-closing means and with said withdrawing member.

6. A power-operated device for pulling nails comprising a rotatable shaft adapted to be connected to a power source, a hammer member on said shaft adapted to rotate therewith and to move axially thereon, an anvil member adjacent said hammer member, a plurality of normally open nail-gripping jaws supported for movement with said anvil member, means biasing said hammer member toward said anvil member, complementary cam portions on said hammer member and said anvil member adapted to cooperate with said biasing means to effect reciprocating movement of said hammer member with respect to said anvil member upon rotation of said shaft to drive said jaws into the surface adjacent a nail to be pulled, a casing supporting said shaft and said hammer member and anvil member, means slidably on said casing forming a collet for closing said jaws in gripping relation with said nail, and means forming a selectively operable driving connection between said shaft and said collet causing said collet to move first into jaw-closing relation with said jaws and thereafter to move beyond said jaws and against said surface to force said jaws and nail away from said surface.

7. In a power-operated nail puller, a casing, a rotatable shaft in said casing adapted to be connected to a power source, a hammer member on said shaft adapted to rotate with said shaft and to move axially thereon, an anvil member in said casing adjacent said hammer member, normally open nail-gripping jaws carried by said anvil member, means biasing said hammer member toward said anvil member, means cooperating with said biasing means to effect reciprocating movement of said hammer member with respect to said anvil member upon relative rotative movement of said hammer member and said anvil member to drive said nail-gripping jaws into the surface adjacent a nail to be pulled, jaw-closing means supported by said casing for first closing said jaws to grip said nail and for thereafter forcing said jaws and said nail away from said surface to withdraw said nail, and selectively operable means for connecting said jaw-closing means with said shaft.

8. A nail pulling device adapted for use with a power source, comprising a rotatable shaft having a threaded portion thereon, means for connecting said shaft to said power source, a hammer member on said shaft adapted to rotate therewith and to move axially thereon, an anvil member adjacent said hammer member, normally open nail-gripping jaws supported for movement with said anvil member, means for effecting reciprocating movement of said hammer member with respect to said anvil member upon rotation of said shaft to drive said jaws into the

surface adjacent a nail to be pulled, a member for closing said jaws supported for axial movement with respect to said shaft, threaded members supported on said closing member for movement therewith and normally spaced from said shaft, and means for bringing said threaded members into cooperative engagement with said threaded portion of said shaft for causing said axial movement of said closing member to close said jaws on said nail and to press said closed jaws and nail away from said surface.

9. A power-operated nail-pulling device comprising an outer casing, an inner casing adapted for axial movement within said outer casing, a rotatable shaft within said inner casing adapted to be connected to a power source, an anvil supported in said inner casing for limited axial movement therein, normally open nail-gripping jaws supported by said anvil, a hammer adjacent said anvil mounted for reciprocating axial movement on said shaft and adapted to rotate with said shaft, means biasing said hammer toward said anvil, cam means on adjacent faces of said hammer and said anvil cooperating with said biasing means to effect reciprocating movement of said hammer toward and away from said anvil upon rotation of said shaft for driving said jaws into the surface surrounding a nail to be pulled, means for effecting relative axial movement of said outer casing and said inner casing upon rotation of said shaft, and means for causing said jaws to grip and to withdraw said nail upon said relative axial movement of said outer and said inner casings.

10. A power-operated nail puller comprising a casing, a rotatable shaft in said casing, said shaft having a threaded portion thereon, means for connecting said shaft with a power source, a hammer member on said shaft adapted for axial movement thereon and for rotation therewith, an anvil member in said casing adjacent said hammer member, said hammer member and said anvil member including cooperating cam surfaces on adjacent faces thereof, normally open nail-gripping jaws carried by said anvil member, means biasing said hammer member toward said anvil member and adapted to cooperate with said cam surfaces for effecting reciprocating axial movement of said hammer member with respect to said anvil member upon rotation of said shaft to drive said open nail-gripping jaws into the surface surrounding a nail to be pulled, a member carried by said casing in initially spaced relation with said surface adapted to move axially of said shaft toward said surface for closing said jaws, said member having a portion thereof adapted on said axial movement to press against said surface and to force said jaws in gripping relation with said nail away from said surface, and threaded means carried by said axially movable member for releasable engagement with said threaded portion of said shaft to cause said axial movement of said movable member.

11. In a power-operated nail puller, a casing, a rotatable shaft in said casing adapted to be connected to a power source and having a threaded portion thereon, a hammer member on said shaft adapted to rotate with said shaft and to move axially thereon, an anvil member in said casing adjacent said hammer member, normally open nail-gripping means carried by said anvil member, means biasing said hammer member toward said anvil member, means cooperating with said biasing means to effect reciprocating movement of said hammer member with respect to said anvil member upon relative rotative movement

of said hammer member and said anvil member to drive said nail-gripping means into the surface adjacent a nail to be pulled, a collet supported by said casing for axial movement with respect to said shaft to close said gripping means, blocks supported for movement with said collet and normally spaced from said threaded portion of said shaft, said blocks having threaded portions for cooperative gripping engagement with said threaded portion of said shaft on movement into engagement therewith, and a lever for effecting movement of said blocks into said cooperative gripping engagement with said threaded portion

of said shaft for causing said axial movement of said collet to close said nail-gripping means on said nail and to press said closed nail-gripping means away from said surface to withdraw said nail.
